[57] CLAIM

The ornamental design for an extruded framing channel
for a glass block, as shown and described.

DESCRIPTION

FIG. 1 is a fragmentary perspective view of an extruded
framing channel for a glass block showing my new
design;

FIG. 2 is an end elevational view thereof;

FIG. 3 is a side elevational view thereof;

FIG. 4 is a fragmentary bottom plan view thereof; and,
FIG. 5 is an enlarged fragmentary right side elevational
view thereof.

The broken line showing of the portion of a glass block
is for illustrative purposes only and forms no part of the
claimed design.
